UNITED STATES PATENT OFFICE.

WILLIAM P. KESEL, OF NEW YORK, N. Y., ASSIGNOR TO CUMMINGS CORPORATION, OF PHILADELPHIA, PENNSYLVANIA, A CORPORATION OF DELAWARE.

DESIGN FOR A DISPLAY STAND.

Application filed January 24, 1928. Serial No. 25,008. Term of patent 3½ years.

To all whom it may concern:

Be it known that I, WILLIAM P. KESEL, a citizen of the United States, and a resident of New York city, in the county of New York and State of New York, have invented a new, original, and ornamental Design for Display Stands, of which the following is a specification, reference being had to the accompanying drawing, forming part hereof.

The figure is a perspective view of a display stand, showing my new design.

I claim:

The ornamental design for a display stand, as shown.

WILLIAM P. KESEL.
